UNITED STATES PATENT OFFICE.

CALVIN DEAN AND ERNEST F. RUECKERT, OF PROVIDENCE, RHODE ISLAND; SAID RUECKERT
ASSIGNOR TO SAID DEAN.

PIN.

No. 921,517.

Specification of Letters Patent. Patented May 11, 1909.

Application filed August 6, 1908. Serial No. 447,313.

To all whom it may concern:

Be it known that we, CALVIN DEAN and ERNEST F. RUECKERT, both citizens of the United States, each residing at Providence, 5 in the county of Providence and State of Rhode Island, have invented certain new and useful Improvements in Pins, of which the following is a specification.

Our invention relates to pins, brooches and 10 similar articles of personal adornment.

The essential objects are strength, sightliness, cheapness and simplicity. Particularly is it sought to provide means for eliminating completely the usual "joint" or 15 "ears" which have been expensive to manufacture, weak and unsightly in use, and have invited entanglement of adjacent fabric; also to avoid the use of independent pivot pins which tend to work out of their bearings; 20 to provide a more efficient form of pin tongue and one whose stop shall be below the surface of the base plate.

To the above ends essentially our invention consists in the novel construction and 25 combination of parts hereinafter described, and illustrated in the accompanying drawings wherein,

Figure 1, is a plan elevation of the original blank constituting the base plate of a pin embodying our invention. Figs. 2 and 3, 30 sections on line X X of Fig. 1, showing respectively, the pivot member in normal and elevated positions. Fig. 4, a side elevation of my novel pin tongue. Fig. 5, a perspective view of adjacent portions of the pin tongue and base plate during the engagement of the two parts. Fig. 6, a plan elevation of the back of a complete pin and Figs. 7 and 8, sections on lines Y Y and Z Z respectively of Fig. 6.

Like reference characters indicate like parts respectively, throughout the views.

The base plate A of my pin is cut from a thin metallic strip into a preferably oblong 45 form with an integral lateral lug B near one end. Near its opposite end the plate A is inwardly cut from its side margin to form a transverse opening, a, extending to a longitudinally disposed aperture, a', the whole 50 forming a T shaped opening, with resultant oppositely disposed lugs, a² and a³. Extending from the plate A at the base of the aperture, a', to the margin of the plate, and intermediate the portions a² and a³ is a projection 55 C which forms the pivot member for a pin

tongue. After the described blank has been cut the free end of the projection C is elevated as shown in Figs. 3 and 5 to receive the pin tongue. Any convenient and usual form of pin tongue may be employed. In this instance it comprises a pointed shaft D having a downwardly bent or offset flattened portion E expanded at its end into a substantially circular flat head F provided with a central perforation, f, and a horizontally disposed circumferential stop lug, f', upon its bottom. The tongue is applied to the base A by passing the head F down over and along the inclined member C, as shown in Fig. 5, so that the lug, f', shall pass below the surface 70 of the plate A, and the head F shall enter the aperture, a'. The projection C is then bent back into the plane of the plate A, and the pin tongue is pivotally held upon the member C against lateral movement by the members a² and a³. The lug B is bent as usual to form the pin catch. The contact of the lug, f', against the face of the plate A insures a sufficient tension upon the pin shaft D to press the latter tightly upward against the 75 top of the catch B.

Any desired form of ornamental front, G, may be applied to the plate A by solder or otherwise. In this instance the front plate G has its margin, g, rolled over the margin 80 of the plate A.

What we claim is,

1. An article of manufacture comprising a base plate provided with a transverse marginal slot and a longitudinally disposed aperture into which the slot leads, an integral projection at the base of the aperture extending into the slot, and a catch upon the plate. 90

2. An article of manufacture comprising a base plate, a pivot member integral with the plate at one end having its opposite end free and normally lying in the plane of the plate, and a catch upon the plate. 95

3. An article of manufacture comprising a base plate provided with an opening, a pivot member integral with the plate at one end and having its opposite end free and extending into the opening and a catch upon the plate. 100

4. An article of manufacture comprising a base plate provided with a marginal slot, and an aperture into which the slot leads, and a projection at the base of the aperture extending into the slot, and a catch upon the plate. 110

5. An article of manufacture comprising a base plate provided with an opening, and a pivot member integral with the plate at one end and having its opposite end free and extending into the opening.
6. A pin tongue comprising a shaft, a head, an inclined portion connecting the shaft and head, and a lug upon the head disposed at an angle to the inclined portion and parallel with the shaft.
7. In a pin of the type set forth, the combination with a base plate, of a pivot member upon the plate, a catch upon the plate, a front plate mounted upon the base plate, a pin shaft provided with an inclined portion adjacent the head, a head upon the end of the inclined portion provided with an opening to receive the pivot member, and a lug upon the head disposed at an angle to the inclined portion and parallel with the shaft, adapted to engage the base plate.
8. In a pin of the type set forth, the combination with a base plate, of a pivot member integral with the plate at one end and having its opposite end free of the base plate and in the plane of the plate, a catch upon the plate, a front plate mounted upon the base plate, and a pin tongue mounted upon the pivot member.
9. In a pin of the type set forth, the combination with a base plate, of a pivot member integral with the plate at one end and having its opposite end free of the base plate, a catch upon the plate, a front plate mounted upon the base plate, and a pin tongue mounted upon the pivot member.
10. In a pin of the type set forth, the combination with a base plate provided with an opening, a pivot member integral with the plate at one end and movable out of the plane of the plate and extending into the opening, a catch upon the plate, a front plate mounted upon the base plate, and a pin tongue mounted upon the pivot member.
11. In a pin of the type set forth, the combination with a base plate, a pivot member integral with the plate, a catch upon the plate, a front plate mounted upon the base plate, a pin shaft, a head upon the shaft provided with an opening to receive the pivot member, and a lug upon the head adapted to engage the inclosed face of the base plate.
12. In a pin of the type set forth, the combination with a base plate provided with an opening, a pivot member integral with the plate at one end and movable out of the plane of the plate and extending into the opening, a catch upon the plate, a front plate mounted upon the base plate, a pin shaft, a head upon the shaft provided with an opening to receive the pivot member, and a lug upon the head intermediate the plates.
13. In a pin of the type set forth, the combination with a base plate provided with an opening, a pivot member integral with the plate and extending into the opening, a catch upon the plate, a front plate mounted upon the base plate, a pin shaft provided with a bent end portion, a head upon the end of the bent portion of the shaft mounted upon the pivot member, and a lug upon the head adapted to engage the base plate.
- In testimony whereof we have affixed our signatures in presence of two witnesses.
- CALVIN DEAN.
ERNEST F. RUECKERT.
